US00D634007S

(12) **United States Design Patent**
Zinger et al.

(10) **Patent No.:** **US D634,007 S**
(45) **Date of Patent:** **** Mar. 8, 2011**

(54) **NEEDLELESS ADDITIVE CONTROL VALVE**

(75) Inventors: **Freddy Zinger**, Ra'anna (IL); **Igor Denenburg**, Beberi (LV); **Niv Ben Shalom**, Netanya (IL)

(73) Assignee: **Medimop Medical Projects Ltd.**, Ra'anana (IL)

(**) Term: **14 Years**

(21) Appl. No.: **29/334,693**

(22) Filed: **Mar. 31, 2009**

(51) **LOC (9) Cl.** **24-02**

(52) **U.S. Cl.** **D24/129**

(58) **Field of Classification Search** D24/129,

CLAIM

The ornamental design for a needleless additive control valve, substantially as shown and described.

DESCRIPTION

FIG. 1 is a right front perspective view of a needleless additive control valve in accordance with our new design;

FIG. 2 is a right rear perspective view thereof;

FIG. 3 is a front elevation view thereof;

FIG. 4 is a right elevation view thereof;

FIG. 5 is a rear elevation view thereof;

FIG. 6 is a left elevation view thereof;

FIG. 7 is a top plan view thereof; and,

FIG. 8 is a bottom plan view thereof.
